EDWARD KIRBY BOTTLE, OF ELMIRA, NEW YORK, ASSIGNOR TO AMERICAN SALES BOOK COMPANY, LIMITED, OF TORONTO, ONTARIO, CANADA, A CORPORATION OF ONTARIO, CANADA

MANIFOLDING BOOK

Application filed April 7, 1923. Serial No. 630,576.

This invention relates to an improvement in manifolding books and with respect to its more specific features to four copy books.

An object of the invention is to provide a manifolding book wherein four copies may be simultaneously made with a single transfer leaf.

Another object is to provide in a manifolding book composed of an assemblage of sets of more than two record leaves, an arrangement such that a single transfer leaf may be used, and may be inserted between the leaves of a set and removed therefrom without touching the same.

Another object is to provide in a book of the class described, an arrangement of leaves in the set, which will materially reduce the thickness of the book.

Another object is to provide in a book composed of an assemblage of four record leaf sets, an arrangement of the leaves in the set and of the sets, such that the thickness of the book will be materially reduced, and a single transfer leaf may be used.

Other objects of the invention will be in part obvious and will in part appear hereinafter.

The invention accordingly comprises an article of manufacture possessing the features, properties, and the relation of elements which will be exemplified in the article hereinafter described and the scope of the application of which will be indicated in the claims.

In the accompanying drawing forming a part of this specification wherein similar reference characters refer to similar parts throughout the several views,

Figure 1 is a perspective view of the improved book, with a part of the first leaf broken away,

Fig. 2 is a similar view showing the two-leaf set folded into a four-leaf set,

Fig. 3 is a perspective view of an alternate form of transfer leaf, and

Fig. 4 is a top plan view showing an alternate arrangement of transfer leaf.

In the embodiment of the invention shown in Figs. 1 and 2, the improved book consists of a plurality of sets of leaves, each set in-

cluding a leaf 1 and a leaf 2, of approximately the same record length, and which are connected at one end, as for instance by a line of paste indicated at 3. At the opposite end the leaves 1 of all of the sets are connected together, as for instance by binding, and in the present instance the connection is made by staples 4 which are passed through all of the leaves 1, and a suitable back 5 of pasteboard or the like.

The back 5 is preferably relatively stiff as compared with the leaves of the book supported thereon and, as shown, extends approximately the full length of the leaves 1 and 2 so as to support the latter in the book in the position shown in Figure 1. The manifolding leaves 1 and 2 are manipulated from the position shown in Figure 1 into the position in which they are used during a manifolding operation as more fully later appears.

The improved book may consist of as many sets of leaves as may be desired, and a transfer sheet, or leaf is provided in connection with each book. The transfer leaf indicated at 6, in the present instance a double-faced leaf, is bound with the sets by the staples 4. The transfer leaf is of a length such that it will lie between the leaves 1 and 2, and will extend from the binding of the book to near the connected ends of the leaves of the sets, and also will extend across the fold lines 7, hereinafter further mentioned. Any desired form of ruling and printed matter may be arranged on the leaves of the sets. In the usual arrangement all of the leaves of a set have a common number, and the sets are numbered consecutively. Each two-leaf set is designed to be folded into a four-leaf set, so that four copies may be simultaneously obtained by writing on the uppermost of the four. Hence, the printing and ruling is so arranged upon the leaves of the sets, that each leaf 1 and 2 will have two sets of substantially duplicate matter, the upper half containing one set, and the lower half the other set. Since the two-leaf sets are designed to be folded into four-leaf sets, an indicating line of fold 7 is provided in connection with each leaf, and the lines of fold

of all the leaves are in substantial register. The line of fold may be a crease, or merely an indicating line, or, as in the present instance, it may be a line of partial separation, to facilitate the detachment of the copies of each leaf from each other. In addition a line of partial separation 8 is provided near the connection of the leaf 2 with the leaf 1, and a similar line 9 is provided for the leaf 1 near its connection with the binding. Thus the upper half of the leaf 2 may be separated from the lower half, or the entire leaf 2 may be separated from the leaf 1. In addition, the lower half of the leaf 1, together with the leaf 2 may be separated from the upper half of the leaf 1, or all four copies may be separated from the binding. The transfer leaf is notched in one side edge as indicated at 10, near its connection with the binding, to facilitate engagement of a pencil or the like with the leaf, to remove it from between the leaves of a set, or to insert the same. However, it is not necessary to at any time touch the transfer leaf, since it may be placed between the leaves of a set, or removed therefrom, by manipulation of the book.

As will be observed in Figures 1 and 2, transfer material may be applied on both faces of the transfer leaf substantially throughout the length thereof. When the transfer material is thus applied, the inscriptions are transferred to the back side of the original record leaf which is the leaf disposed on top as the leaves are assembled, as shown in Figure 2. This inscription is, of course, a reverse inscription and is useful in preventing frauds by erasures or alterations, although in some instances, as shown in Figure 3, it is unnecessary that the face of the transfer leaf lying against the back of the original record leaf be supplied with transfer material.

To insert the transfer leaf between the leaves, the leaf 2 is turned down, and the book is flipped upward and forward, throwing the transfer leaf on top of the leaf 1, after which the leaf 2 may be turned back into normal position. During this manipulation the outer ends of the lower record leaf 1 and of the transfer leaf 6 are supported in extended position by means of the back 5. This facilitates the adjustment of the leaves into correct position for manifolding operation and prevents tearing or other injury to the record and transfer leaves. In order that four impressions may be obtained from one transfer leaf, the leaf 2 is of tissue or other translucent material. When the leaves of a set are folded on the fold line, with the transfer leaf in place, as shown in Fig. 2, and the lower half of the leaf 1, which is now the uppermost leaf of the set, is written upon, four copies will be made.

It is not necessary that all of both faces of the transfer leaf be provided with transfer

material. As shown in Fig. 3, a transfer leaf 6^a may have one face and half of the other face provided with transfer material 11, the lower half of the said face being plain as indicated at 12. Neither is it essential that the transfer leaf be connected at the ends of the leaves 1, as is done in the embodiment of Figs. 1 and 2. For example, as shown in Fig. 4, the record book indicated at 13 is the same in general construction as that shown in Fig. 1, but, in this case, the transfer leaf 14 has an extension 15 at one side edge, and at one end, and this extension is secured to the back 5 in any suitable or desired manner, as for instance by pasting or stapling. The extension 15 is of such length that it stops short of the fold line 7, and it may be inserted between the leaves of a set, and removed therefrom by manipulation of the book as above described. That is the upper leaf of the set is turned back, the transfer leaf is flipped into place after which the top leaf is returned to normal position, and the leaves of the set are folded. At no time is it necessary to handle the transfer leaf in the operation of the improved book.

Since certain changes may be made in the above article and different embodiments of the invention could be made without departing from the scope thereof, it is intended that all matter contained in the above description or shown in the accompanying drawing shall be interpreted as illustrative and not in a limiting sense.

Having described my invention, what I claim as new and desire to secure by Letters Patent, is:

1. In a manifolding book of the character described, in combination, sets of two superposed record leaves pasted together at one end and having registering weakening fold lines intermediate their ends, a transfer sheet adapted to be disposed between said leaves, said sheet having upper and lower transfer faces at one side of said fold lines, said transfer sheet having a side extension positioned wholly at one side of said fold lines by which it is adapted to be connected to the book.

2. A manifolding book including, in combination, a plurality of superposed sets of record leaves, each set including two superposed record leaves of approximately similar record length and having transfer fold lines substantially in registry with each other intermediate the ends of said leaves, one end of the lower of said leaves of each set having a binding to bind it to the book, the leaves of each set being attached together at their other ends, a stiff supporting back extending from said binding of the record leaves substantially the full extended length of said leaves so as to support the sets of superposed leaves in extended position in the book, and a transfer sheet connected to the book so as to be interposed between the leaves of the

uppermost of said sets and extending across
said fold lines approximately to the point of
attachment between said leaves, said transfer
sheet having an upper transfer face opposite
5 the portion of the upper record leaf between
the fold line in the latter and its attachment
with the other record leaf, said transfer sheet
having upper and lower transfer faces op-
posite the portions of said record leaves be-
10 tween said fold lines and the binding of the
sets of leaves.

3. A manifolding book including, in com-
bination, sets of two superposed record leaves
secured together at one end and having trans-
15 verse weakening fold lines intermediate their
ends dividing them into two record sections,
one of said record leaves of each set having
a binding at one end to the book, a transfer
sheet of a length to overlap both said record
20 sections and adapted to be disposed suc-
cessively between the record leaves of the sets
and having a side attaching extension at-
tached to the book and lying wholly between
the fold lines and said binding.

25 In testimony whereof I affix my signature.
EDWARD KIRBY BOTTLE.
